Primary Examiner — Ralf Seifert(74) *Attorney, Agent, or Firm* — Andrew F. Young, Esq.; Lackenbach Siegel, LLP(57) **CLAIM**

The ornamental design for a jasmine cut diamond, as shown and described.

DESCRIPTION

FIG. 1 is a left front top perspective view of the present invention.

FIG. 2 is a left side elevation view of FIG. 1.

FIG. 3 is a right side elevation view of FIG. 1.

FIG. 4 is a rear side elevation view of FIG. 1.

FIG. 5 is a front side elevation view of FIG. 1.

FIG. 6 is a top plan view of FIG. 1.

FIG. 7 is a bottom plan view of FIG. 1; and,

FIG. 8 is a right rear top perspective view of the present invention for assistive purposes.

The surfaces are lightly lined for contour only.

1 Claim, 6 Drawing Sheets
